Attorneys.

UNITED STATES PATENT OFFICE.

JOHN O. LUDWIG, OF CINCINNATI, OHIO, ASSIGNOR TO THE SCHUSTER COMPANY, OF CLEVELAND, OHIO, A CORPORATION OF OHIO.

DESIGN FOR A FLASK.

47,795.

Specification for Design.

Patented Sept. 7, 1915.

Application filed April 8, 1915. Serial No. 20,058. Term of patent 14 years.

To all whom it may concern:

Be it known that I, JOHN OTTO LUDWIG, a citizen of the United States, residing at Cincinnati, in the county of Hamilton and State of Ohio, have invented a new, original, and ornamental Design for a Flask, of which the following is a specification, reference being had to the accompanying drawing, forming part hereof.

The figure is an elevation of said flask, showing the form in which the same may be used.

I claim—

The ornamental design for a flask, as shown.

J. O. LUDWIG.

Witnesses:

FRED W. SCHWENCK,

F. H. WULFHORST.
